Application October 20, 1936, Serial No. 106,650

8 Claims. (Cl. 66—8)

This invention relates to improvements in methods and machines for knitting improved elastic topped stockings.

The primary object of this invention is the provision of improved means for knitting a stocking having an elastic top which will effectively grip the leg of a wearer and remain in position without discomfort.

A further object of the invention is the provision of an improved elastic topped stocking, such as adapted to be worn by men, having an elastic top which is rather loosely knitted relative to the leg of the stocking and having elastic means therein which will grip the leg of the wearer and hold the stocking in place without discomfort and without stopping the blood circulation.

A further object of this invention is the provision of an improved stocking knitted after an improved method and upon an improved machine whereby the stockings may be continuously knitted in stringwork upon the same machine, and which stocking embodies an improved elastic top which will effectively and comfortably grip the leg of a wearer and hold the stocking in place.

Other objects and advantages of this invention will be apparent during the course of the following detailed description.

In the accompanying drawings, forming a part of this specification, and wherein similar reference characters designate corresponding parts throughout the several views,

Figure 1 is a fragmentary front elevation of a machine upon which the improved stocking may be knitted.

Figure 2 is a developed view of the needle, jack, and cam set-up for the improved machine.

Figure 3 is a side elevation of the stocking showing diagrammatically the manner in which the elastic top of the stocking is knitted.

Figure 4 is a fragmentary perspective view showing the manner in which the elastic yarn is incorporated in the top portion of the stocking with the inelastic yarn.

Figure 5 is a plan view of the cylinder and latch ring assembly showing the main and auxiliary feeds, etc.

Figures 6 and 7 are diagrammatic developed views of the cam lug pattern set-up upon the pattern drums of the improved machine.

Figure 8 is an enlarged outer view of a portion of the fabric which may be knitted upon the machine using the set-up shown in Figure 2; the view showing the relative stitch arrangement in

the top and leg of the stocking and at the juncture of the elastic top and leg.

Figure 9 is a view similar to Figure 8, but showing the inside of the fabric.

Figure 10 is a developed view showing another needle, jack and cam set-up for the knitting of an elastic topped stocking which is differently knitted at the juncture of the elastic top and leg of the stocking.

Figure 11 is an enlarged fragmentary view showing the stitch arrangement of the fabric as knitted with the needle set-up shown in Figure 10 and wherein at the juncture of the elastic top and leg portions of the stocking certain tuck stitches are provided for the purpose of producing a neat and effective connecting section between the elastic top and leg portion.

Figure 12 is a fragmentary front elevation of a modified form of fabric.

Figure 13 is an inside view of the fabric shown in Figure 12.

In the drawings, wherein for the purpose of illustration are shown preferred and modified forms of the invention, the letter A may generally designate the improved knitting machine which includes a supporting frame B having a cylinder C rotatably supported thereon. The machine is generally of the type set forth in my copending application Serial No. 730,666, filed June 14, 1934, now Patent No. 2,164,119, and as set forth in that application is adaptable to be used for the knitting of "color within color" patterning in the leg or other portion of the stocking. To that end the machine includes a latch ring C' having a main feed arrangement B' for the feed of different yarns to the needles, and an auxiliary feed arrangement D thereon. A set of needles E are provided upon the machine having a set of control jacks F associated therewith. Wrap patterning means G is provided for the feeding of different fancy wrap yarns to the needles in a selected "color within color" arrangement, as has been more specifically described and set forth in my above identified co-pending application.

The machine may or may not be used with the wrap patterning arrangement, since the primary object of this invention is the provision of an improved elastic topped stocking.

The machine furthermore includes a cam actuating pattern drum H and a yarn feed finger controlling pattern drum K.

The stockings K are knitted in continuous stringwork, and each has an improved elastic top. The machine due to the manner of knitting the

top is capable of knitting the stockings efficiently and economically in stringwork.

The top of the stocking has incorporated elastic and inelastic yarns, and is so knitted that it will efficiently adhere to and conform to the leg of the wearer for the purpose of holding the stocking against slipping down upon the leg. To that end the inelastic yarn stitches in the top of the stocking are relatively loose, inasmuch as the stitches are interknitted upon a less number of needles of the cylinder of the machine than the number of needles utilized in knitting the leg portion of the stocking. The number of needles used in knitting the top of the stocking may be optional. That is, alternate needles of the cylinder may be utilized for knitting the top of the stocking, whereas all the needles are utilized in knitting the leg of the stocking, or, as is preferred, only one third of the needles (every third needle) may be used in knitting the top of the stocking, whereas all of the needles are utilized in knitting the leg of the stocking. In addition, it is preferred not to place the elastic yarn in every course of the inelastic yarn in the top of the stocking, but only in alternate courses, or, if desired, in any desired spacing. An additional factor is the interknitting of the elastic yarn together with the inelastic yarn in each stitch in each of the courses wherein the elastic yarn is knitted in the top of the stocking.

The cam actuation of the jacks and needles may best be described in sequence. Starting with the knitting of the loopers round at the end of the stocking toe, the same is knitted at the regular feed with the heel and toe yarn 20, shown in Figure 2 of the drawings, on every needle of the machine. The loopers round extends for any desired number of courses and at the end, the main body or leg yarn 21 is also fed to all of the needles of the knitting machine in addition to the heel and toe yarn 20, in order to prevent a run-back into the loopers round, because on the next move of the machine the needles which are inactive during knitting of the top of the next stocking are buried.

The needle actuating cam 23 is thrown into action by a leverage mechanism 24 shown in Figure 1 of the drawings, which in turn is controlled off of the pattern drum H, in accordance with the cam set-up shown in Figure 6 of the drawings, as will be subsequently mentioned. This cam 23 elevates all of the cylinder needles in order to shed the stitches thereof below the latches of the needles, preparatory to burying the cylinder needles which are inactive during knitting of the rib top. In the present machine only every third needle is utilized in knitting the top of the stocking.

Cam 25, which is operated off of a leverage mechanism 26, is thereafter used to lower all of the cylinder needles which have been elevated by the cam 23, to their normal position, with the stitches still hung on the needles but externally on the closed latches of the needles. At the same time cam 27 which is operated off of a leverage mechanism 28, shown in Figure 1, is thrown into position for elevating certain jacks 30 which are disposed below every third needle of the machine, and which jacks have upper long butts and short lower butts. The cam 27 operates on the upper long butts and elevates said jacks 30 for throwing the needles which are active during knitting of the elastic top upwardly into position for taking yarn. In this position

75 I knit for four courses with the body yarn 21,

as above described, in order to crowd the stitches at the end of the loopers round preparatory to dropping the needles which are inactive during knitting of the elastic top. This yarn 21 of course knits on all of the needles of the machine notwithstanding that the cam 27 has elevated every third needle, and these four courses comprise the selvage.

In the next course the auxiliary feed yarn 35 is thrown into action by its finger shown in Figure 2 of the drawings, and at the same time the auxiliary knitting cam block 36 is also thrown into position for actuating the needles of the machine at the auxiliary feed. This auxiliary block is operated by leverage mechanism 37, 15 shown in Figure 1 of the drawings, controlled off of drum H. The binding yarn (body yarn) 21 is now thrown out of action thru its leverage mechanism controlled from drum J, and the heel and toe yarn 20 remains in action. Channel cam 40 is then thrown into position to act on the needles to be buried (inactive during knitting of the top of the stocking); this cam 40 being actuated off of the leverage mechanism 41 shown in Figure 1 of the drawings. It should be remembered that the cam 27 was previously thrown into action to elevate every third needle, so that the cam 40 is now in position to act in burying the other two needles of each group of three needles. The selvage of the stocking is now knitted for approximately thirty-six courses on every third needle of the cylinder machine. This is ordinarily waste, except for the part which is sewed inside of the top of the stocking (as shown at 46 in Figure 3 of the drawings) to form the welt. Of course the welt may be formed otherwise than in this manner.

In the next move of the pattern drum the elastic yarn 50 is thrown into position for feeding onto every third needle of the machine, and together with the inelastic heel and toe yarn 20 knits on said every third needle in alternate courses. Both feeds of the machine are active; the yarns 20 and 50 feeding at the main feed, and the inelastic yarns 35 feeding at the auxiliary feed. The yarns 20 and 21 are ordinary inelastic yarns, while the yarn 50 is elastic commercial "Lastex." Cams 21, 23, 25, and 40 are of course retracted as the first course of the elastic top of the stocking is knitted. This top continues through any desired number of courses, preferably two hundred and forty, and of course it can readily be understood from the set-up above described that the elastic yarn is knitted in every stitch in alternate courses of the top of the stocking, but of course the top of the stocking is only knitted upon every third needle of the cylinder. The auxiliary feed yarn 35 and the feed yarn 20 at the main feed are heavier than the leg yarn 21. The looseness of stitches is due to knitting on every third needle of the machine. The fact that the yarns are heavier than the leg yarn and that the elastic yarn is only knitted in alternate courses, but on every stitch in each course in which it is knitted, gives the top of the stocking not only a very efficient lateral and longitudinal elasticity, but gives it a mock rib effect.

The manner of adding the other needles to take the yarns, and the change of yarns, at the juncture of the top of the stocking and the leg may be variously accomplished. In the set-up shown, the cam 55 after knitting the top of the stocking, but while still utilizing the yarns 20, 35 and 50 is thrown into action by the mechanism

56 shown in Figure 1, operating off of the pattern drum H, for the purpose of elevating the other jacks 31, which have long butts at their lower ends. These jacks 31 are below one of the normally inactive needles during top stocking knitting, and their elevation by the cam 55 throws the needles thereabove into position for also taking the same yarns at the main and auxiliary feeds as every third needle of the machine does 5 during knitting of the major portion of the top of the stocking. The machine may then make any desired number of revolutions. Preferably one, two, or three revolutions are sufficient, and of course both feeds are active and the elastic 10 yarn 50 is also fed to the needles thus elevated. It should be remembered that one needle in every three is still buried. This needle is elevated by the cam 60, which is thrown into action off of leverage mechanism 61 shown in Figure 1 of the 15 drawings, operating off of pattern drum H, and now all of the needles of the machine are in position for taking the yarns at the main and auxiliary feeds. One or more courses may thus be knitted utilizing both feeds of the machine, 20 with the yarns 20, 35 and 50 active. Preferably only one course is thus knitted and then the auxiliary cam block 36 is thrown out of action; the heel and toe yarn 20 is thrown out of action and also the auxiliary feed yarn 35 and the 25 elastic yarn 50. The body yarn 21, which is preferably of silk, is thrown into action. This all preferably takes place during one course of knitting and now we knit the leg of the stocking on every needle of the machine. 30

35 At the heel and toe of the stocking a cam 10 is provided to raise the long butt cylinder needles above the stitch cam arrangement at the main feed, in order that they may idle. This is of course conventional in that the heel and toe are 35 both knitted upon the short butt needles. The leg or body yarn 21 is of course retracted and the heel and toe yarn 20 used at these locations.

40 At completion of knitting the heel and toe the cam 25 is thrown into action by the means above described to lower the long butt cylinder needles preparatory to full circular knitting. At the end of the reciprocatory toe knitting the loopers round is again knitted in the manner above described and the cycle is completed. In 45 this manner the stockings are continuously 50 knitted in stringwork.

In Figure 3 of the drawings the heavy horizontal lines 75 designate the courses in which the elastic yarn is knitted, and the lighter horizontal lines 76 designate those courses which are formed solely by the inelastic auxiliary yarn 35. 55

In Figure 4 is more clearly designated in full lines the knitting of the courses out of the elastic yarn 50; the dotted lines represent the stitches formed by the inelastic auxiliary yarn 35. The 60 yarn 20 of course is knitted into the same stitches as the elastic yarn 50, but this heel and toe yarn 20 is not shown in Figure 4. In this figure is also shown at 77 the manner of floating the elastic yarn from course to course wherein the 65 same is knitted.

Referring to Figures 8 and 9 of the drawings 70 therein is designated respectively the outside and inside of the seamless fabric knitted in the manner above described. The numerals designate the various yarns 20, 21, 35 and 50. The knitting proceeds in the direction indicated by the arrow and it is thus seen that every alternate course 75 designated at 80 has both the inelastic yarn 20 and the elastic yarn 50 knitted together in every

stitch thereof; the elastic yarn being under sufficient tension to prevent undue spreading of the stitches lengthwise and cross-wise. The alternate courses 81 are knitted (in the top) out of the inelastic yarn 35 at the auxiliary feed. The 80 stitches formed in the course designated at 82 are formed on two out of every three needles of the knitting machine, that is, after the cam 55 has gone into action to elevate the jacks 31 and the needles thereabove as above described. This 85 course 82 is formed of both the yarns 20 and 50. The next course 83 is produced on two out of every three needles of the machine, with every third needle buried, the same as the preceding course, but the elastic yarn does not appear in 90 this course, inasmuch as it is knitted out of the auxiliary yarn 35. The next course designated at 95 84 is knitted the same as the course 82. Thereafter all of the needles of the machine are thrown into action and the next four or five courses are 100 knitted on every needle of the machine out of the heavier inelastic yarns 20 or 35, or out of both of said yarns. These yarns are of course heavier than the silk leg yarn 21, and as shown in Figures 8 and 9 the silk leg yarn 21 is thereafter 105 knitted on every needle of the machine, and is continued throughout the leg of the stocking, with the exception of the heel and toe, as above outlined.

Figures 12 and 13 show by way of modification 110 fabric which is knitted with the top drawn a little tighter than the top of the stocking above described, inasmuch as the top of the stocking is knitted on every other needle (instead of every third needle). Thus the fabric shown in Figures 115 12 and 13 has the courses 90 formed of an inelastic yarn 20^a and an elastic yarn 50^a at the main feed of the machine, and the alternate courses 91 are formed of merely an elastic yarn 35^a at the auxiliary feed of the machine. At the 120 juncture of the top of the stocking with the leg portion 93 every needle of the machine is brought into play and takes the yarns as shown in Figures 12 and 13, although some variation at this juncture point may be made if desired. Preferably 125 in order to draw the stitches tightly and prevent large openings at the juncture of the top of the stocking and the leg the elastic yarn is continued throughout the first course knitting on every needle when going into the leg. 130

As will be noted from Figures 1 and 2 of the drawings various cams, yarn fingers and yarn guide and control members are shown in dotted lines. These may be used upon the present machine when the latter has a set-up for the knitting of patterned wrap yarns. They need not be specifically described herein, but have the same characteristics as specifically set forth in my application Serial No. 730,666, filed June 14, 1934. 135

In Figure 10 is shown a developed needle and 140 jack cam set-up for the knitting of fabric having elastic incorporated as above described, but in which set-up the cam arrangement is relatively simpler and capable of producing tuck stitches at the juncture of the leg with the top of the stocking, so as to obviate large openings occurring at this section, as shown in Figure 11 of the drawings. 145

In connection with the set-up shown in Figure 10, when knitting the elastic top of the stocking 150 shown in the lower portion of Figure 11, every third needle is utilized and takes the body yarn 100 at the auxiliary feed, and at the main feed the alternate courses are knitted out of the heel and toe yarn 101 and the elastic yarn 102, in

the same manner as above described for the fabrics illustrated in Figures 8 and 9. The knitting of the top proceeds in substantially the same manner as above described for the needle set-up 5 shown in Figure 2, so far as the top is concerned. When we reach the course designated at 105 in Figure 11 of the drawings, at the auxiliary yarn feed, the yarn 106 is not only fed to every third needle utilized during knitting of the previously knitted courses in the top, but the adjacent needle, normally idle during knitting of the top, is elevated. These two needles, that is, the regular every third needle 107 on which knitting is effected for producing the major portion 15 of the top of the stocking and the needle 108 to be elevated for forming the tuck stitches, are elevated as shown in the right hand portion of Figure 10 for taking the yarn 106. This elevation of the needles 108 is accomplished by means of a cam 109 acting on the special jacks 110. The cam 111, also at this location, acts on the special jacks 112 to elevate the needles 107. It is only on the needles 108 that the tuck stitch is knitted at the auxiliary feed. During the same 20 revolution of the cylinder that the needles 108 are elevated to take the auxiliary yarn for knitting the tuck stitches, the cam 113, shown in Figure 10, elevates the needles 107 for taking the heel and toe yarn 101 and the elastic yarn 102, 25 and it is noted that the needles 108 are not elevated at this regular feed. Thus at the auxiliary feed, as shown in Figure 11, the regular stitches 120 are produced, and a tuck stitch 121 is produced which is not thrown off at the next course 30 knitted at the regular feed. However, during the succeeding revolution of the cylinder the needles 108 are again elevated at the auxiliary feed and the stitches hung thereon are then cast off to start another row of tuck stitches upon the needles 108. It will thus be noted, from Figure 35 11, that at the juncture of the leg portion 130 of the stocking with the top of the stocking the stitches formed are quite closely packed together to present a neat section without openings. About four courses are knitted at this section; 40 the tuck stitches of course extending through two tuck stitch courses, as shown in Figure 11. The elastic yarn is withdrawn at the start of knitting upon all of the needles of the cylinder, but the 45 yarns 100 and 101 are knitted on part of the needles for approximately four courses shown at 131, and then the leg yarn 133 is dropped into action upon all of the needles.

The stitch cams at the auxiliary and main feeds need but little description, since their function will be apparent to one skilled in the art, from the above description and from the illustration in Figure 10. At the auxiliary feed the stitch cam block 140 has a cam edge 141 in position to lower all of the needles which are at the normal level, that is, those needles not elevated by the cams 109 and 111, and this cam 140 also has a cam edge 142 which lowers the needles elevated by the cams 109 and 111.

At the regular feed a cam 145 normally lowers all needles at the normal level, except those elevated by the cam 113. The rest of the stitch cam set-up is conventional.

It will be noted in Figures 2 and 10 that certain butts on the needles and jacks are either short or medium length. This is to enable the insertion of the actuating cams.

The yarns, including the elastic yarn, are fed under some tension to needles of the machine.

It is of course understood that the stocking

may be knitted otherwise than herein described, such as upon a machine by first knitting the leg portion and then the top portion, and that the machine may be of the stationary cylinder type wherein the cam set-up rotates.

Referring to Figure 6 of the drawings, the same shows the cam lay-out for the pattern drum H. The lugs on the dot and dash line 200 actuate, through the leverage mechanism above described, the cam 40; the lugs on the dot and dash lines 201 actuate, through leverage mechanism, the cam 27; the lugs on the dot and dash lines 202 actuate certain of the jack cams shown in dot and dash lines in Figure 2 of the drawings, but which are not necessary so far as the present invention is concerned, since it primarily relates to the provision of an elastic garter top stocking. The lugs on the lines 203 through leverage mechanism, are used to actuate, the cam 25. The lugs on the line 204 are used to actuate through leverage mechanism 207, shown in Figure 1, the yarn guide wires or members as has been described in my above identified co-pending application, but which need not necessarily be used with the present invention. Lugs along the line 208 are used to actuate certain feed fingers forming a part of my above identified co-pending application; the lugs along the line 209, through leverage mechanism, are used to actuate the cam 23; lugs along the line 210 are used to actuate the auxiliary 25 knitting block 36; the lugs along the line 211 are used to actuate the cam 60; the lugs along the line 212 are used to actuate the cam 55; the lugs along the line 213 are used to actuate the cam 70; the lugs along the line 214 are used to actuate the binder and cutter mechanism, as has been described in my above identified co-pending application, and the lugs along the line 215 are used to actuate the auxiliary feed finger which feeds the yarn 35.

In Figure 7 is shown the pattern lug lay-out on the drum J for actuating the feed fingers at the regular feed. The lugs along the line 216 are used to actuate the feed finger for the silk leg yarn 21; the lugs along the line 217 are used to actuate the feed finger for the elastic yarn 50; the lugs along the line 218 are used to actuate the feed finger for the heel and toe yarn 20. The other lugs along the other lines may be used for actuating feed fingers for other yarns, if desired.

From the foregoing description it is apparent that an improved machine has been produced for the automatic knitting of elastic topped stockings in stringwork after an improved method. The stocking itself has an elastic top which is distinctly different from anything heretofore produced. It has not only lateral but longitudinal elasticity sufficient to enable it to effectively and comfortably grip the leg of the wearer and retain the stocking in place without slipping. The top 60 of the stocking has a mock rib effect which is primarily produced because of the incorporation of the loose stitches, although the stitches are not loose enough to leave voids or openings, due to the manner in which the elastic yarn is incorporated. The incorporation of the elastic yarn by knitting it directly in each stitch in each alternate course wherein it is knitted produces the highly desirable result of longitudinal and lateral elasticity. The position of the yarns is 65 such that they will not become displaced due to washing of the stocking. Furthermore no unsightly marks will be left upon the leg of the wearer nor will the blood circulation be retarded.

Various changes in the shape, size, and arrange- 75

ment of parts may be made to the form of invention herein shown and described, without departing from the spirit of the invention or the scope of the claims.

5 I claim:

1. In a knitting machine a circular line of needles, a main feed having non-elastic and elastic yarns thereat, an auxiliary feed having a non-elastic yarn thereat, means during a single revolution of the cylinder to produce two courses by feeding both the non-elastic and elastic yarns at the regular feed and non-elastic yarn only at the auxiliary feed upon the needles of the knitting machine, means at each of said feeds for interknitting in fabric the yarns so fed to said needles, and means for dividing the needles of each of said feeds in a selected manner for knitting a portion of the stocking upon only occasional needles throughout the circle of needles.
- 10 2. In a knitting machine a circular line of needles, a main feed having non-elastic and elastic yarns thereat, an auxiliary feed having a non-elastic yarn, means during alternate revolutions of the cylinder to feed both the non-elastic and elastic yarns of the main feed to alternate needles of the cylinder, means during the other revolutions of the cylinder to feed the non-elastic yarn of the auxiliary feed to the same alternate needles to produce a tubular fabric together with the yarns of the main feed, and means for feeding a leg knitting yarn to all of the circular line of needles to knit a leg integrally with the top of the stocking.
- 15 3. In a knitting machine a circular line of needles, means for feeding an elastic yarn only to regularly and recurrently spaced needles of the cylinder during alternate revolutions of the cylinder, means for feeding in inelastic yarn to said recurrently spaced needles during the remaining revolutions of the cylinder to produce together with said elastic yarn a stocking top wherein alternate courses are inelastic and the remaining courses elastic with a two-way stretch, and means for knitting a leg portion of a stocking upon all of the needles of the cylinder and integrally connected with said top.
- 20 4. The method of knitting a stocking which consists in knitting a seamless top of both elastic and inelastic yarns in interknitted relation to produce a two-way stretch therein, subsequently knitting a leg connecting portion having tuck stitches in continuance with the spaces between the wale lines of the top and having smaller stitches than the top in continuance with the wale lines of the top, and subsequently knitting a leg portion in integrally connected relation with said connecting portion wherein the stitches are appreciably smaller than the stitches of either the top or connecting portion.
- 25 5. The method of knitting a tubular stocking upon a circular line of cylinder needles which consists of knitting a top portion of inelastic

yarn upon the circular line of cylinder needles by feeding said inelastic yarn to every third needle of the cylinder, interknitting with the stitches of relatively spaced courses an elastic yarn under sufficient tension to draw the stitches of the inelastic yarn together for producing a simulated rib top of plain knitting, and subsequently feeding inelastic yarn to all of the cylinder needles to produce an integrally connected leg portion.

10 6. The method of producing a tubular stocking top which consists of feeding yarn to less than one-half of regularly recurrently spaced needles of a circular line of needles and during the knitting of occasional courses of the inelastic yarn feeding to the said regularly recurrently spaced needles an elastic yarn under sufficient tension to draw the inelastic yarn stitches and wale lines of the top together in simulation of a rib top.

15 7. The method of knitting a tubular stocking on a circular line of cylinder needles with integrally connected top and leg portions which consists in feeding inelastic yarn to every third needle of the circular line of needles with two needles in the circular line between the needles which receive said inelastic yarn inactive during knitting of the top, and during the knitting of certain courses of inelastic yarn in the top feeding an elastic yarn to those needles which receive the inelastic yarn in the top, with said elastic yarn under sufficient tension to tend to draw the wale lines of the top together in simulation of a regular rib top, subsequently adding another of the needles of the circular line of needles which are inactive during knitting of the top to receive the elastic and inelastic yarns of the top to produce a joining portion between the top and the leg portion of the stocking of a limited number of courses, and subsequently knitting a leg portion of inelastic yarn upon all of the needles of the circular line of needles.

20 8. The method of knitting a seamless stocking fabric upon a circular line of cylinder needles which consists of knitting a leg portion of inelastic yarn upon all of the cylinder needles, and knitting a top welt portion of inelastic yarn upon only regularly spaced needles of the cylinder appreciably fewer in number than the needles on which the leg portion is knitted and during the knitting of the top welt portion drawing the stitches longer and wider than the stitches in the leg portion, and also during the knitting of the top portion knitting in with the stitches thereof an elastic yarn under sufficient tension to normally draw the stitches of the top portion together in simulation of a rib top and to enable the said top portion to have a two-way stretch both circumferentially and longitudinally without unduly distorting the top portion inelastic yarn stitches.

25 30 35 40 45 50 55 60 HARRY McADAMS.
